UNITED STATES PATENT OFFICE.

MATTHEW L. HOYT, OF LITTLEFALLS, NEW YORK, ASSIGNOR TO D. H. BURRELL & COMPANY, OF LITTLEFALLS, NEW YORK.

DRIVING MECHANISM FOR CENTRIFUGAL SEPARATORS.

SPECIFICATION forming part of Letters Patent No. 744,966, dated November 24, 1903.

Application filed November 23, 1901. Serial No. 83,412. (No model.)

To all whom it may concern:

Be it known that I, MATTHEW L. HOYT, a citizen of the United States, and a resident of Littlefalls, in the county of Herkimer and State of New York, have invented a new and useful Improvement in Driving Mechanism for Centrifugal Separators, of which the following is a specification.

This invention relates to the devices where-
10 by the spindles of centrifugal separators are rotated, and has special reference to the class of separators in which the bowl is frequently required to be detached from the driving mechanism and removed from the support-
15 ing-frame for cleaning the bowl, as is the case, for instance, in centrifugal creamers. The spindles of cream-separators are rotated either by a steam-turbine applied directly to the spindle or by a pulley and belt or similar
20 device or by a gear mechanism which is operated by hand. In the particular kind of separators in question the spindle is permanently or otherwise attached to the bowl or drum in such manner that it is removed
25 therewith.

One object of the invention is to couple the turbine or other driving device to the spindle by such means that the driving device remains properly supported in the frame when
30 the bowl and spindle are withdrawn, so that the spindle can be again inserted without difficulty into the driving device and can be coupled thereto.

Another object of the invention is to cen-
35 ter the turbine or other driving device by the spindle, so that although the driving device is detachable from the spindle no bearing is required in addition to the usual neck and step bearings in which the spindle is jour-
40 naled at its upper and lower ends.

In the accompanying drawings, consisting of three sheets, Figure 1 is a sectional elevation of a centrifugal creamer embodying my invention. Fig. 2 is a front elevation of the
45 same. Fig. 3 is a horizontal section in line 33, Fig. 1. Fig. 4 is a sectional elevation of the turbine-driving mechanism shown in the preceding figures, but on a greatly-en-
50 larged scale. Figs. 5 and 6 are horizontal sections in lines 55 and 66, Fig. 4, respectively. Fig. 7 is a fragmentary sectional ele-

vation of a pulley-driving mechanism embodying my invention. Fig. 8 is a fragmentary vertical section showing a modified construction of the lower end of the spindle and its bearing. Fig. 9 is a sectional elevation of the separator, showing the same provided with a hand driving mechanism instead of a turbine mechanism. Fig. 10 is an elevation at right angles to Fig. 9.

Like letters of reference refer to like parts in the several figures.

A represents the bowl or drum of the separator, and *a* the spindle, which is secured to the same in any suitable manner.

The supporting-frame may be of any suitable construction, that shown in the drawings being composed of an upper bowl-shaped part B, in which the bowl A is arranged, an intermediate spherical part B', in which the driving device is arranged, and a lower part B'', having the form of a stand or foot of greater or less height.

b b' represent the usual receptacles mounted upon the frame around the top of the bowl 75 for receiving the separated liquids, such as cream and skim-milk.

C, Figs. 1 and 4, represents the upper or neck bearing, which is arranged, as usual, in the upper part of the frame for supporting 80 the spindle below the bowl. This bearing is mounted in any suitable and well-known manner so that it can yield laterally to a certain extent. As indicated in Fig. 4, it is surrounded for this purpose by a spring *c*.

D is a cylindrical sleeve, which is arranged in the upper part of the frame and which receives the neck-bearing in its upper portion. The intermediate portion B' of the frame is provided at its upper end with a collar *b*', 90 which projects upwardly through the bottom of the upper frame part B. The sleeve is provided at its upper end with a flange which rests upon the collar *b*', and the neck-bearing is provided at its upper end with a flange *c*', 95 which rests upon the sleeve D. The neck-bearing is somewhat smaller in diameter than the sleeve D, so that it can move laterally in the same, and the spring *c* is interposed between the neck-bearing and the sleeve. The neck-bearing is held against upward movement in the sleeve by a screw-bolt *c*', which is

arranged horizontally in the upper portion of the intermediate frame part B' and extends through an opening in the sleeve D into an annular groove c³, formed in the neck-bearing, 5 near the lower end thereof. This bolt also prevents the sleeve from turning in the frame. Upon withdrawing this bolt the neck-bearing and the sleeve can be lifted out of the frame. The sleeve D extends downwardly into the 10 upper portion of the intermediate frame part B' and engages with its lower end the upper end of the turbine-casing E and secures or locks the latter in the frame. The casing is provided with an upwardly-projecting neck e, 15 having an internal shoulder e' and around said shoulder a collar e², which surrounds the lower end of the sleeve D. This holding or locking sleeve or member, which is movable in the axial direction of the casing, is released and raised from the casing when the 20 latter is to be removed from the frame.

F represents a steam-turbine wheel of any suitable construction arranged in the casing E. This turbine-wheel is provided with a hollow hub f, which extends with its upper end into the neck of the casing E and which is slightly smaller in diameter than the internal diameter of said neck, so that the hub in its normal position does not touch the neck, but 25 is prevented by the latter from getting so far out of its normal position when the spindle has been withdrawn that it would be difficult to insert the spindle. The upper end of the hollow hub f is provided with an internal collar 30 f', which fits snugly around the spindle and which contains a suitable coupling device—for instance, a key or pin f², which projects into a groove f³ in the spindle. The portion a' of the spindle below the groove is slightly 35 smaller in diameter than the portion in which the groove is arranged, so that the groove opens downwardly and can be passed over the projecting inner end of the coupling pin or key in inserting the spindle. The hollow hub 40 f is provided with a contracted lower end f⁴, which fits snugly around the lower portion of the contracted part a' of the spindle, so that the hub is centered at both ends on the spindle. The contracted part a' of the spindle is 45 provided with a steep multiple screw-thread or worm a² when the machine is designed to be convertible into a hand-machine. The lowermost portion a³ of the spindle is still further reduced in diameter to form a centering end 50 of small diameter and is surrounded by a flanged sleeve g, upon which the spindle a rests by the shoulder a⁴ at the upper end of its lowermost portion a³. The flange g' at the upper end of the sleeve g projects outwardly 55 beyond the reduced portion a', on which the lower end of the hub is fitted, and the lower end of the hub rests upon this projecting top flange, so that the sleeve is rotated by frictional contact with the hub. This sleeve or 60 short tubular spindle is preferably supported by a ball-bearing consisting of a ball-cone h, formed on the under side of the top flange

of the sleeve, balls h', and a ball-cup h². The latter is seated or formed in the top of a step H, which is secured in the lower portion of the intermediate frame part B'. This step has a central opening in which the lower portion of the sleeve turns. 70

I represents a retaining-cap which is secured to the projecting upper end of the step H, preferably by a screw-thread, as shown. This cap has an upwardly-projecting marginal flange i, which confines the lower end of the lower neck e³ of the turbine-casing. The cap has also an inwardly-projecting flange i', 80 which confines the lower end of the turbine-hub, and the cap serves further to hold the ball-cup in the step H. 85

The spindle is free to be lifted out of the bearings and out of the hub of the turbine or other driving device. Upon removing the spindle the hub is retained in its normal position at the lower end by the retaining-cap I and at the upper end by the upper neck e of the turbine-casing, so that the spindle can 90 be conveniently inserted and coupled with the driving device after the bowl has been cleaned.

The spindle is supported directly upon the step-bearing and the driving device is separately supported upon this bearing, whereby the driving device is relieved from the load on the spindle. The removal of the spindle or of the driving device, or both, does not disturb the parts of the step-bearing, which latter 100 remains intact.

In order to facilitate the operation of engaging the groove of the spindle with the coupling pin or key of the hub of the turbine or other driving device, a holding device is provided, which can be pressed against the hub for holding the latter against turning while the spindle is being inserted. As shown in Figs. 1, 3, and 4, this holding device is mounted on the turbine-casing and is constructed as follows: K represents a horizontal holding pin or ball which is arranged in front of the turbine-hub near the upper end of the latter. L represents a socket arranged in the upper portion of the turbine-casing. 110 The inner portion k of the pin is smaller in diameter than the outer portion k' and terminates near the turbine-hub, while the outer portion projects through an opening in the front plate m of the intermediate frame part B' and forms a thumb-piece for pressing the pin backward against the hub. The pin is held in its outermost or retracted position by a spring k², which is seated in the inner portion of the socket L and bears against a collar 115 k³ on the pin. The outward movement of the pin is limited by a stop-pin l, against which the collar k³ is held by the spring, Fig. 4. When the spindle is to be inserted, the holding-pin is pressed against the upper end 120 of the turbine-hub, whereby the latter is prevented from turning. This enables the operator to readily engage the groove of the spindle with the coupling pin or key. 125

The front plate m of the housing, which is formed by the intermediate frame part B' , is removably secured to the latter by bolts m' or other suitable fastenings and is provided with a hollow boss m^2 for the steam-inlet pipe m^3 of the turbine and a hollow boss m^4 for the exhaust-pipe m^5 , Figs. 1, 2, and 3. The intermediate frame part B' and the sleeve D , in which the neck-bearing is arranged, are provided with coinciding openings $n n'$, Figs. 1 and 4, through which access can be had to the spindle in balancing the bowl.

O, Fig. 4, represents a speed-indicator of well-known construction, which may be mounted in the upper portion of the front plate m . The worm-wheel o' of this indicator is pressed in a well-known manner against a worm o^2 , formed on the upper portion of the spindle, for taking the speed. The sleeve D is provided on its front side with an opening o^3 , through which the speed-indicator projects toward the spindle.

Fig. 7 shows my invention embodied in a power driving device in which a pulley is mounted on the spindle and rotated by a belt, cord, or rope. The spindle and bearings are constructed and arranged as above described. P represents the pulley, which is shown as a grooved pulley, but may be of any other suitable construction. p is the hub of the pulley, which is constructed with a contracted lower end p' , by which it is centered on the spindle and by which it rests upon the flanged sleeve g . The upper portion of the hub is provided with a coupling pin or key p^2 , which engages with the groove of the spindle, and the upper end of the hub is loosely centered on the lower end of the sleeve D by a marginal flange p^3 or other suitable means.

In the modified construction of the spindle-step (represented in Fig. 8) the rotary member at the lower end of the spindle, which is the sleeve g in the construction shown in Figs. 1, 4, and 7, is a journal composed of an upper portion G , a lower portion G' , and an intermediate flanged disk G^2 . The upper portion G of the rotary member is arranged in a socket formed centrally in the lower end of the spindle, the lower portion G' turns in the step-bearing G^3 upon a ball G^4 , and the flanged disk G^2 projects laterally beyond the spindle and supports the hub f of the driving device. When the spindle is withdrawn, this rotary member remains in the bearing and supports the driving device.

The turbine-driving mechanism (shown in Figs. 1 to 6) can be readily replaced by a hand driving mechanism, as represented in Figs. 9 and 10. For that purpose the turbine and its casing and the front plate m are removed and a hand driving mechanism of any suitable construction is substituted, which may consist, briefly stated, of a housing Q , which takes the place of the front plate m , a worm-wheel q' , which meshes with the worm a^2 , a pinion q^2 , secured to the shaft q^3 of the worm-wheel, a driving gear-wheel q^4 , which meshes

with the pinion q^2 and is mounted upon a shaft q^5 , and a hand-crank q^6 , secured to the shaft q^5 . By supplying both a turbine mechanism and a hand driving mechanism with the same separator the user is enabled to employ the turbine mechanism in the summer, when much milk is to be separated, and the hand mechanism in the winter, when but little milk is to be separated.

The oil-passages are arranged in such manner that the oil is conducted from the upper or neck bearing to the lower or step bearing. As shown in Fig. 4, the neck-bearing is provided at its top with a depressed annular oil-receptacle r , from which an oil-duct r' leads to the inner surface of the bearing. The upper portion of the hub which fits around the spindle is provided with an oil-duct r^2 , through which the oil which has flowed down along the spindle enters the cavity of the hub. The oil passes from the bottom of this cavity by a duct r^3 to the top of the retaining-cap I and from the latter by a duct r^4 to the ball-bearing.

I claim as my invention—

1. The combination of a rotary spindle, a supporting-frame, a holding-sleeve arranged in said frame, a spindle-bearing arranged in said sleeve, and a fastening device which is attached to said frame and engages both said sleeve and said bearing, whereby the sleeve and the bearing are both secured and released by the same device, substantially as set forth.

2. The combination of a rotary spindle, a supporting-frame, a holding-sleeve arranged in said frame, a spindle-bearing arranged in said sleeve and provided with an annular groove, and a fastening-bolt attached to said frame and projecting through an opening in said sleeve into the groove of said bearing, substantially as set forth.

3. The combination of a removable rotary spindle, a supporting-frame, a removable holding-sleeve capable of vertical movement in said frame, a spindle-bearing arranged in said sleeve, and a driving device arranged below said sleeve, the latter engaging with its lower end the upper end of the driving device, whereby the driving device is retained laterally in position by said sleeve when the spindle is withdrawn, substantially as set forth.

4. The combination of a rotary spindle, a step-bearing on which the same is supported, and a driving device surrounding said spindle, the spindle and driving device being capable of free vertical movement with reference to each other and said driving device being supported on said bearing independently of said spindle, substantially as set forth.

5. The combination of a rotary spindle, a step-bearing on which the same is supported, a driving device surrounding said spindle, the spindle and driving device being capable of free vertical movement with reference to each other and said driving device being supported on said bearing independently of said spindle, and means for coupling said spindle

with said driving device and permitting the ready removal of the spindle therefrom, substantially as set forth.

6. The combination of a rotary spindle, a step-bearing on which the same is supported, a driving device surrounding said spindle, the spindle and driving device being capable of free vertical movement with reference to each other and said driving device being supported on said bearing independently of said spindle, and a coupling projection and upright groove in said spindle and driving device, substantially as set forth.

7. The combination of a rotary spindle, a step-bearing provided with a ball-cone on which the spindle is supported, and a driving device surrounding said spindle, capable of free vertical movement thereon, and supported independently thereof on said ball-cone, substantially as set forth.

8. The combination of a rotary spindle, a step-bearing on which the same is supported, a driving device surrounding said spindle, the spindle and driving device being capable of free vertical movement with reference to each other and said driving device being supported on said bearing independently of said spindle, means for detachably coupling the spindle with the driving device, and means for centering the driving device when the spindle is withdrawn, substantially as set forth.

9. The combination of a rotary spindle, a step-bearing on which the same is supported, a driving device surrounding said spindle, the spindle and driving device being capable of free vertical movement with reference to each other and said driving device being supported on said bearing independently of said spindle, means for retaining the driving device laterally in position on said bearing when the spindle is withdrawn, and a holding device retaining the upper end of said driving device laterally in position when the spindle is withdrawn, substantially as set forth.

45 10. The combination of a spindle, an upper and a lower bearing, a holding-sleeve which extends below the upper bearing, a turbine-casing which is centered at its upper end by said sleeve, and a turbine-wheel which is centered on the spindle and confined laterally at its upper end by said casing when the spindle is withdrawn, substantially as set forth.

11. The combination of a spindle, an upper and a lower bearing, a turbine-wheel which is centered on the spindle, means for detachably coupling the spindle with said wheel, a retaining device applied to the lower bearing and holding the lower portion of the wheel in position when the spindle is withdrawn, a turbine-casing, and means for supporting the same, substantially as set forth.

12. The combination of a spindle, an upper and a lower spindle-bearing, a turbine-casing arranged between said bearings, and an axially-movable locking member for holding said turbine-casing in position, substantially as set forth.

13. The combination of a spindle, an upper and a lower spindle-bearing, a turbine-casing arranged between said bearings, and a holding-sleeve which is movable toward and from the end of said casing and by which the latter is held in position, substantially as set forth.

14. The combination of a spindle, an upper and a lower bearing, a holding-sleeve which carries the upper bearing, a turbine-casing which is centered at its upper end by said sleeve, a turbine-wheel which is centered on the spindle and held in position at its upper end by said casing when the spindle is withdrawn, and a lower retaining device which holds the lower portion of the wheel in position when the spindle is withdrawn and which supports the turbine-casing, substantially as set forth.

15. The combination of a spindle, an upper and a lower bearing, a holding-sleeve which carries the upper bearing, a turbine-casing which is centered at its upper end by said sleeve, a turbine-wheel which is centered on the spindle and held in position at its upper end by said casing when the spindle is withdrawn, and a retaining-cap on which the casing is supported and which is provided with a marginal flange which centers the lower end of the casing and with an inner retaining-flange which centers the lower end of the wheel, substantially as set forth.

16. The combination of a spindle, an actuating device into which the spindle can be inserted and from which it can be withdrawn, a holding device adapted to be pressed against the actuating device for holding the latter against rotary movement when inserting the spindle, and a stationary support for said holding device, substantially as set forth.

17. The combination of a spindle, an actuating device into which the spindle can be inserted and from which it can be withdrawn, a spring-bolt which can be pressed against the actuating device for holding the latter against rotary movement when inserting the spindle, and a stationary support for said spring-bolt, substantially as set forth.

Witness my hand this 20th day of November, 1901.
